UNITED STATES PATENT OFFICE.

FRANCIS J. SHEPHARD AND HENRY FORNCROOK, OF CONCORD, WISCONSIN.

RAILROAD-SIGNAL.

SPECIFICATION forming part of Letters Patent No. 429,390, dated June 3, 1890.

Application filed August 26, 1889. Serial No. 321,932. (No model.)

To all whom it may concern:

Be it known that we, FRANCIS J. SHEPHARD and HENRY FORNCROOK, of Concord, in the county of Jefferson, and in the State of Wisconsin, have invented certain new and useful Improvements in Railroad-Signals; and we do hereby declare that the following is a full, clear, and exact description thereof.

Our invention relates to railroad-signals; and it consists in certain peculiarities of construction, as will be fully set forth hereinafter and subsequently claimed.

In the drawings, Figure 1 is a plan view of the operating portions of our device, partly broken away. Fig. 2 is a side elevation thereof, also partly broken away; and Fig. 3 is a detail sectional view on the line 3 3 of Fig. 1.

A represents one rail of an ordinary railroad-track, and B B two of the supporting ties thereof, which extend some little distance beyond the outside of said rail, preferably farther than the other ties C C, the ties B B being united outside of said rail by cross-ties D D. From each tie B to the adjacent tie C beyond it we extend a wear-plate E, and to headed bolts a a, projecting up from said wear-plate, are secured the slotted ends of a spring F, (preferably a semi-elliptic leaf-spring, as shown,) the elongated slots b in said spring ends receiving the shanks of the said bolts a, the heads of said bolts extending transversely across and over said slots.

G is a double bell-crank lever, the short inner arm e of which is pivoted, as at d, to the bifurcated pendent ends of a hanger e, secured to the under side of the spring F, at the center thereof, and the horizontal portion of the double bell-crank G is journaled in boxes f f on the cross-ties D D, while the long outer arm g of said double crank G projects upward in an approximately vertical position and has an eye h at its upper end, by which it is connected to a rod H, or a cord, wire, or chain i, as preferred.

I is a post placed adjacent to the highway at the point crossed by the railroad-track, and J is a bell secured to said post and connected, as by a cord, chain, wire, or rod i, to the rod, wire, cord, or chain H, or to a continuation of the same, it being our intention to place our spring and lever at a point considerably distant from the post I, the latter being near the

actual point of crossing of the railroad and highway, the bell (or other signal, if preferred) on said post being connected to said lever by 55 the line H i, which may of course be of any length preferred, though from one to two thousand feet being an average good distance.

The operation of our device will be readily understood from the foregoing description of 60 its construction. When the wheels of a railway-train pass over the track at the point where our device is located, the tread of each wheel, as shown at K in dotted lines in Fig. 3, will press down on the spring F, and the 65 depression of the spring (whose slotted ends enable this to be done without injury) also depresses the short arm e of the double crank-lever G and draws the long arm g of said lever to the position shown in dotted lines in 70 Fig. 2, thereby also drawing upon the line H i and ringing the bell J or actuating any other signal used in place of or in addition to said bell, and thereby giving instant and timely warning at the crossing a thousand feet, more 75 or less, distant of the approach of the train, the bell J being rung, of course, with every wheel that passes over the spring F.

In order to prevent the spring F from being crowded away from the track by the 80 wheels so as to be rendered inoperative, we preferably employ a guard or keeper L, which may be made in one piece with the wear-plates E, if desired, as shown in Fig. 1, secured to the ties B B, and preferably centrally 85 braced, as by brace-rod M, bolted to said guard and to the outer cross-tie D.

We may vary the form or style of our spring, if desired, but have found the form shown to work well in practice. 90

When in any instance we may desire to have the bell continue to ring for a longer time than usual, we may unite the rod H to the long outer arm g by a slot and wrist pin in place of the connection shown, and then 95 the vibrations or oscillations of the bell will continue for a considerably longer period than with the style of connection shown in the drawings.

Having thus described our invention, what 100 we claim as new, and desire to secure by Letters Patent, is—

The combination, with the wear-plates adapted to be secured parallel with the rail

and the guard connecting said wear-plates and arranged to extend parallel with the rail, of the semi-elliptical leaf-spring interposed between the guard and rail and having longitudinally-elongated slots in its ends and resting at said ends upon the wear-plates, the bolts projecting upward from said wear-plates and through the slots in the spring, the pendent hangers upon the underside of said spring, 5 the rock-shaft having at one end the short rock-arm pivoted at its upper end between said pendent hangers, and the long vertical vibrating arm carried by the opposite end of 10

the rock-shaft and connected, substantially as described, to a bell or other signal, for the 15 purpose set forth.

In testimony that we claim the foregoing we have hereunto set our hands, at Oconomowoc, in the county of Waukesha and State of Wisconsin, in the presence of two witnesses.

FRANCIS J. SHEPHARD.
HENRY FORNCROOK.
